TWISTER

Daniel W. Maxham, Austell, Ga.

Application April 1, 1937, Serial No. 134,403

8 Claims. (Cl. 117—9.5)

This invention relates to an improved twister which is more particularly intended for use for twisting threads during the manufacture of yarn.

One object of the invention is to provide a 5 twister which will impart two turns or twists to threads entering the flyer employed at each revolution of said flyer.

Another object of the invention is to provide a 10 twister employing means for permitting the package or bobbin to be quickly removed from the flyer so that a great deal of doffing time will be saved and thus much more running time allowed, with consequent greater production of yarn at a 15 minimum overhead cost.

A further object of the invention is to provide 20 a twister having a balanced flyer which is adapted to rotate about the package at high speed and thus permit the uniform winding of a relatively large package of twisted yarn in a relatively short time, and with minimum danger of breaking or 25 roughing of said yarn.

A further object of the invention is to provide 30 a device of this character which will take up minimum space and which will be highly efficient 25 so that a minimum amount of waste will take place.

And a still further object of the invention is to 35 provide a twister which will be relatively simple in construction and durable in use so that it may be kept in service for long periods of time without the necessity for repair.

Other and incidental objects of the invention not specifically mentioned hereinbefore will render themselves apparent during the course of the 35 following description.

My improved twister is illustrated in the accompanying drawings, wherein:

Figure 1 is a plan view of my improved twister and showing it mounted in operative position.

40 Figure 1a is a detail plan view showing a portion of the traverse motion mechanism.

Figure 2 is an enlarged fragmentary vertical sectional view of the device.

Figure 3 is a horizontal sectional view on the 45 line 3—3 of Figure 2, looking in the direction indicated by the arrows.

Figure 4 is a horizontal sectional view on the line 4—4 of Figure 2.

Figure 5 is an enlarged horizontal sectional 50 view of the feed rollers employed and showing the manner of winding the twisted yarn about said rollers preparatory to feeding the yarn to the package or bobbin.

Figure 6 is a fragmentary plan view showing 55 one means for driving the flyer.

Figure 7 is a fragmentary plan view showing a modified form of driving mechanism for the flyer.

Figure 8 is an enlarged vertical sectional view, partly shown in elevation, and showing a modified form of twister.

Figure 9 is a horizontal detail sectional view on the line 9—9 of Figure 8, looking in the direction indicated by the arrows.

Referring now more particularly to the drawings, wherein like numerals of reference will be seen to designate like parts throughout the various views, the numeral 1 indicates in general a creel which is provided with a number of thread carrying bobbins 2. The creel may be mounted in any suitable manner above, or, if desired, below my improved twister.

In carrying my invention into effect, and referring particularly to Figure 2 of said drawings, I provide a flyer which is indicated in general by the numeral 3 and includes a tubular substantially rectangular frame having top and bottom portions 4 and 5 and side portions 6 and 7. The side portion 6 is formed with an outwardly opening slot 8 and said top and bottom portions are provided, for a distance substantially half the width of the frame, at corresponding sides thereof, with outwardly opening slots 9 and 10. In order to permit rotation of the flyer about a vertical axis, I provide a hollow spindle or sleeve 11 which is formed medially of the top portion 12 and is adapted to extend upwardly at right angles to said top portion for a relatively short distance. Formed on the frame in axial alignment with the spindle 11 is a trunnion 12. The spindle has its upper end portion journaled in the lower end portion of a former shaft 13 which carries a former including rollers 14 mounted in said former shaft at axial right angles to the axis of said shaft and in vertical staggered relation. The former is adapted to be driven at a speed twice that of the 40 flyer in a manner and for a purpose to be set forth more in detail hereinafter. The former shaft 13 is supported by means of a yoke support 15 which is formed on a spinning machine or other suitable machinery and which has upper and lower legs 16 and 17. The leg 17 terminates at its outer end portion in a bearing 18 which journals the shaft 13 at its lower end portion, said shaft 13 surrounding the upper end portion of the spindle 11 and providing a bearing therefor. A shoulder 19 is formed in the end of the shaft 13 and limits downward movement of said shaft. The leg 16 terminates in a bearing 20 which journals the shaft 13 near its upper end, while a pinion 21 is keyed to said shaft 13 at a 50

55

point below the lowermost roller 14 and above the bearing 18. That is to say, the pinion is disposed between the roller 14 and said bearing 18. A pulley 21 is keyed on the former shaft 13 and is adapted to have a belt 22 trained thereabout for imparting rotative movement to said shaft 13 from a suitable prime mover such as is shown at 23 in Figure 6 of the drawings. A roller 24 is mounted in the frame at the junction of the spindle 11 and the top portion 4, and is adapted to be mounted in the slot 9 to project outwardly thereof. A roller 25 is rotatably mounted in the frame at the junction of the top portion 4 and the side portion 6, the top and side portions being cut away at 6' to receive said roller, while a roller 26 is mounted in the frame at the junction of the lower portion 5 and said side portion 6. An opening 7' is provided to receive the roller 26. A central roller 27 is mounted medially of the bottom portion 5 and is adapted to extend upwardly into the area of the frame.

In order to impart rotation to the flyer, I provide a relatively large gear 28 which is adapted to mesh with the pinion 20, which is relatively small. The gear 28 is keyed on a shaft 28a and carries a gear 29 to rotate therewith, said gears 28 and 29 being keyed on opposite sides of the leg 17 and said gear 29 being adapted to mesh with a gear 30, which gear 30 is substantially twice the size of the pinion 20. The gear 30 is keyed to the spindle 11 and is, of course, adapted to rotate therewith. It will now be understood that, as the pinion 20 is rotated with the shaft 13, rotative movement will be transmitted through the pinion 20 and the gears 28, 29 and 30 to the flyer frame so that the flyer frame will be caused to rotate at substantially half the speed of the former. The flyer frame is provided on the lower extremity of its lower portion 5, in axial alignment with the spindle 11, with an integral depending bearing 31 adapted to rotatably receive or journal a stationary mounting shaft 32 having a stationary pinion 33 keyed thereto.

A relatively small bracket 34 is mounted on the lower portion 5 of the flyer frame substantially medially of the length of said lower portion and near the roller 27 and is formed with an arm 35 which extends in overhanging relation to the roller to lie in axial alignment with the mounting shaft 32 and the spindle 11. The arm 35 is formed with a sleeve 36 having an axial opening 37 therein. A compressor 38 is carried at the under side of the arm 35 and is adapted to compress and guide yarn feeding therethrough. The sleeve 36 is adapted rotatably to carry thereon a bobbin or package mounting shaft 39 which extends upwardly in the flyer frame axially thereof and has an axial downwardly opening socket 40 and a shoulder 41, which shoulder is adapted to abut the upper edge of the sleeve 37 for limiting downward movement of said package mounting shaft. A roller 42 is mounted in the opening formed in the circumferential wall 43 of the package mounting shaft 39 and at right angles to the length of said shaft, while a relatively wide pinion 44 surrounds the package mounting shaft near its lower end and is adapted to rotate freely thereabout and to mesh with a relatively large driving gear 45 which is keyed on the inside of the flyer frame above the bottom portion 5 thereof. The relatively large gear 45 is adapted to have keyed to rotate therewith a gear 46 of like size which is disposed beneath the portion 5. A stem 47 with nuts 48 and 49 at opposite ends thereof, connects the gears 45 and 46 and said gear 46 is

adapted to mesh with a pinion 50 which is carried on the stationary mounting shaft 32. The pinion 50 is adapted to rotate freely about the stationary shaft 32 and has fixed integrally therewith a gear 51 which is adapted to be driven by a worm 52. It should be understood that the worm 52 may be of any desired size for increasing or cutting down the speed of rotation of the gears 50 and 51. If desired, additional gearing may be introduced between the worm and the gear 51 by an integral sleeve 52 while a bearing 53 surrounds the worm 52 and serves to support said gears in proper operative position. Downward displacement of the pinion 50 and gear 51 is further limited by a suitable locking sleeve 54 fixed to the stationary shaft 32.

Carried on the package mounting shaft 39 within the flyer frame is a relatively large bracket 55 which extends from said package mounting shaft laterally to a point near the outside of the frame. The bracket provides a mounting for the yarn feeding motion of my device and is formed with spaced parallel arms 56 and 57 and a depending outer portion 58. Said bracket is adapted to carry feed rollers 59 and 60 which are mounted between the arms 56 and 57 of said bracket 55 in horizontal spaced relation on vertically extending roller shafts 61 and 62. The roller shafts are adapted to have keyed thereon, at their corresponding upper ends, meshing gears 63 and 64. The gear 63 also meshes with a relatively small pinion 65 surrounding the package mounting shaft 39 to rotate freely thereabout and is formed with a package mounting plate or disc 66 which carries a friction disc 67 formed of a suitable fabric secured to its upper side. The roller mounting shaft 62 carries at its lower end a drive gear 68 which is adapted to mesh with the pinion 44. The gear 68 is, as best seen in Figures 1 and 2 of the drawings, disposed directly above the upper surface of the gear 45. A worm 69 is carried on the shaft 61, above the roller 60 and is adapted to drive, through a gear 70, best seen in Figure 4 of the drawings, a shaft 71 having a bevelled gear 72 at its outer end. The shaft 71 and the gear 72 drive a traverse motion which is indicated in general by the numeral 72'. The bevelled gear 72 is adapted to mesh with a bevelled gear 73 which is carried on a traverse motion shaft 74 having its lower end portion 75 journaled in a socket 50 formed in the depending outer portion 58 of the bracket 55. The traverse motion shaft is adapted to extend upwardly throughout nearly the entire height of the frame and is provided with a two-way thread 76. That is to say, the thread 76 is cut in clockwise and in intersecting counterclockwise direction. The traverse motion shaft is journaled at its upper end in the end of a laterally extending bracing arm 77 which is provided at its inner end portion with a socket 78 rotatably receiving the trunnion 72 formed on the frame. By referring to Figure 1a, it will be seen that the traverse motion includes a fixed guide member 77' which has its lower end fixed to the portion 58, said guide member extending upwardly 65 throughout the length of the shaft 76 and having its upper end turned laterally to form a part of said bracing arm 77. The bracing arm 77 has formed integrally therewith a downwardly extending latch 79 which includes a depending latch sleeve 80 having a double bayonet slot 81 formed therein. Carried in the latch sleeve 79 is a latch member 82 including a pin 83 normally engageable in the bayonet slot 81. As best seen in Figure 2, the latch member may be retracted by 75

shifting the pin 83 of the latch member 82 laterally out of the lowermost bayonet slot recess and then upwardly and again laterally into the uppermost bayonet slot recess.

5 The traverse motion includes a feeder sleeve 84 which is carried on the traverse motion shaft 74 and is adapted to be shifted upwardly and downwardly on said traverse motion shaft by rotation of said shaft. That is to say, the beveled 10 gears 72 and 73 cooperate to drive the traverse motion shaft and, as said shaft is driven, the feeder sleeve will be caused to shift upwardly on the threaded portion 76 of said shaft. The feeder sleeve 84 carries a guide arm 284 which 15 has its free end surrounding the member 771. The guide arm 284 serves to prevent rotation of the sleeve 84 and thus to insure vertical travel of said sleeve. After reaching the upper extremity of said shaft, the feeder sleeve will be 20 caused to engage the counter-clockwise thread on said shaft 76 for shifting said sleeve downwardly. The feeder sleeve includes a thread receiving eye 85 which is formed integral with said sleeve.

25 In order to provide a receptacle for the yarn twisted by my device, in a manner to be described hereinafter, I utilize a bobbin or package 86 which is removably carried in the flyer frame 3 and which includes upper and lower portions 87 and 88 and an axial stem 89. The portion 88, when the bobbin is mounted in the flyer frame, is adapted to fit over the upper end portion of the package or bobbin mounting shaft in frictional engagement with the friction disc 67 on 30 the mounting plate 66. The upper portion of the bobbin is formed with a socket 90 which is adapted removably to receive the lower end portion of the latch member 82 when said latch member is in its downwardly extended position. 35 As heretofore stated, for doffing the bobbin, it is only necessary to shift the latch member 81 upwardly so that said bobbin or package may be freed from the latch member and the package mounting shaft. The package mounting shaft is 40 retained stationary with respect to the flyer frame 3 and with respect to the bobbin or package 86. In order to retain the package mounting shaft stationary, as stated, I provide gears 91 and 92 which are of the same size, relatively 45 large, and are fixed to rotate with a shaft 93. The gear 91 meshes with the stationary gear 32 on the stationary shaft 32 while the gear 92 meshes with a gear 94 which is fixed to the package mounting shaft 39 near its lower end. It 50 will be understood that, as the flyer frame 3 rotates about the stationary shaft 32, the shaft 93 with the gears 91 and 92, will be caused to move around with the flyer so that said gear 91 will be caused to rotate about the gear 33 and, 55 therefore, the gear 92 will be caused to rotate about the gear 94 so that said gear 94, carried by the shaft 39, will be maintained in a stationary position with respect to the flyer frame 3. The shaft 39, being fixed to said gear 94 will, 60 of course, be retained stationary with respect to the flyer. A bushing 94' separates the gear 94 from the pinion 44.

It should be understood that suitable housings may be provided for all of the gearing so that 65 oil used for lubricating the gearing will not come in contact with threads being twisted or twisted yarn on the bobbin.

In use, threads from a plurality of bobbins 2 on the creel 1, which threads are indicated 70 positively at 95, are led downwardly through the

compressors 96 which are mounted above the flyer. The threads are led from the compressors 96 over the rollers 14 of the former. As has been stated heretofore, the former revolves at twice the speed of the flyer. From the former 5 rollers the now partially twisted threads are led to the roller 24, along the top portion 4 of the flyer frame 3 therein, over the roller 25, downwardly through the side portion 6 of the flyer frame, about the roller 26, along the bottom portion 5 of the flyer frame and partially about the roller 27. As best seen in Figure 3 of the drawings, the rollers are provided with concave faces so that yarn or threads will not be roughened by contact therewith nor will they tend to slip 10 out of contact with said rollers. Moreover, the slots 8, 9 and 10 in the side portion 6 and top and bottom portions 4 and 5 respectively, permit easy placing of the threads in proper operative position. As the threads pass through the 15 former, a partial twist is given to the threads, as stated, but, as the former rotates at twice the speed of the flyer frame, due to the fact that the pinion 20 and gears 28, 29 and 33 step down the speed of the flyer frame with respect 20 to the speed of the former shaft, half of this twist to the threads comes out before the threads reach the roller 24. The object of the former is to make, in the threads, an outside ply of 25 sufficient length to permit a second twist to be imparted to the threads at the bottom of the flyer. The first twist to the threads is imparted at the top of the flyer, of course. From partially about the roller 27 the now twisted yarn is led upwardly through the compressor 38, 35 through the opening 37 and into the socket 40, partially about the roller 42, about the feed rollers 59 and 60, through the eyes 97 and 98 formed on the bracket 55, through the eye 85, and thence about the stem 89 of the bobbin or 40 package 86. The yarn is wound about the feed rollers in the manner best seen in Figure 5 of the drawings, and said feed rollers are driven by means of the gear 68 which is driven by the relatively wide pinion 44 and the gears 45, 46, 45 50, 51 and the roller 52. The gear 63 drives the gear 64 for rotating the roller 60 in an opposite direction with respect to the roller 59 so that it is necessary to cross the yarn in the manner shown in Figure 5. The gear 63 also drives the 55 pinion 65 for driving the package mounting disc or plate 66 so that the package or bobbin 86 will be caused to rotate for winding the yarn fed thereto through the eye 85 from the rollers 59 and 60, uniformly about the stem 89. As the 60 rollers are rotated, the feeder sleeve is caused to shift upwardly on the traverse motion shaft 75 in the manner set forth, for winding the yarn uniformly along the length of the stem 89 of the bobbin 86 and thus preventing bunching of 65 the yarn. It will be understood that a well balanced package will be provided so that a much larger package of yarn may be twisted. The worm 52, which supplies the rotative movement to the feed rollers, to the traverse motion, and to the bobbin, is driven by a suitable motor or engine, or may be driven from a countershaft connected to associated machinery. It is believed that from the foregoing, it will be clearly understood that I have provided a simple and yet 70 highly efficient twister which will effectively place a double twist in yarn feeding therethrough.

In Figures 6 and 7 of the drawings, means is shown for connecting a prime mover drum, such as shown at 23 in Figure 6, to the former and 75

the flyer frame. In Figure 6, separate belts 99 and 100 are employed for connecting the prime mover drum 23 to a relatively small pulley 101 and a relatively large pulley 102, respectively. Due to the fact that the relatively small and large pulleys are employed, desired relatively different speeds will be transmitted from the prime mover drum to the former shaft and to the flyer frame, so that gearing, such as is shown at 20, 28, 29 and 30, will not be necessary when the structure shown in Figure 6 is employed.

In Figure 7 of the drawings, I have shown the prime movers drums 103 and 104 which are connected by a continuous belt 105 to separate pulleys 106 and 107, the pulley 107 being larger than the pulley 106. By the employment of the driving system shown in Figure 7, it will be possible to place the prime mover drum shaft at right angles to the flyer frame and to the former shaft 20 and it will also be possible to employ separate prime movers.

Aside from the fact that the gearing 20, 28, 29 and 30 is not employed, the operation of the flyer when using either the drive shown in Figure 6 25 or that shown in Figure 7, will be the same.

Referring now to the modification of the invention shown in Figures 8 and 9 of the drawings, the numeral 110 indicates in general a flyer frame which is of substantially the same shape as that 30 of the preferred form of the invention and is provided with tubular side portions 111 and 112 which are connected by a tubular portion 113 having a cut away slot 114 at the junction of the lower end portion of said side portion 111 and 35 said bottom portion 113. A roller 115 is carried in the cut away slot 114 and is adapted to have trained thereabout partially twisted yarn 116. The bottom portion 113 of the flyer frame is provided medially of its width with a depending 40 bearing bracket 117 and an upstanding inverted L-shaped bracket 118 having a hollow base portion 119 leading into a recess 120 formed in the upper surface of the bottom portion 113 above the bearing bracket 117. The bearing bracket 117 includes a bearing 121 adapted to rotatably receive 45 a drive shaft 122 which extends downwardly through a bight portion 123 of the bearing bracket 117 which bight portion has an integral pinion 124 carried thereon. A pinion 125 is fixed to the 50 drive shaft 122 near its upper end. The drive shaft 122 is adapted to carry a spur gear 126 at its lower end and said spur gear is engageable and driven by a worm 127. Surrounding the 55 drive shaft 122 is a drive sleeve 128 which extends upwardly in the bearing bracket and is provided with a pinion 129 at its upper end. The drive sleeve is adapted to rotate with the flyer frame and the pinion 124. In order to drive the flyer, I provide a beveled gear 130 which is 60 adapted to be mounted on a motor, countershaft, or other source of rotative movement and meshes with a beveled gear 131 which is formed integral with a relatively large spur gear 132. The spur gear 132 is mounted on a stub shaft 133, which 65 is mounted on a spinning machine, or other suitable machinery, indicated diagrammatically at 134, and said gear 132 is adapted to mesh with the pinion 124 for rotating the flyer and the drive sleeve 128.

70 Carried by the flyer frame 110 and mounted above and below the lower portion 113 thereof, are relatively large gears 135 and 136, which are keyed to rotate with a common shaft 137. The inverted L-shaped bracket 118 is formed with an 75 upstanding sleeve 138 which provides a bearing

for the lower end portion of a package mounting shaft 139 which is formed with a socket 140 having a roller 141 therein. A shoulder 142, formed in the socket 140, provides a firm seat for the package mounting shaft on the sleeve 138. A relatively wide pinion 143 is freely mounted on said package mounting shaft directly above the sleeve 138 and said relatively wide pinion meshes with the gear 135 and also with a roller driving gear 144 which is mounted on a roller shaft 145. A laterally directed bracket 146 is formed integral with the package mounting shaft and is formed with an extension 147. The bracket 146 is adapted to carry, at a diametrically opposite point with respect to the package mounting shaft, 15 rollers 148 and 149. It will be noted that the rollers are provided with arcuate grooves 150 to receive yarn and it will also be noted that the rollers are tapered in diameter toward their corresponding lower ends. The purpose of the taper 20 is to keep yarn, wound thereabout and being fed therefrom, tight, and to remove any excess stretching thereof. The rollers 148 and 149 are provided with integral gears 150 and 151 which are adapted to mesh with a gear 152 carried on 25 the package mounting shaft 139. The roller 149 is provided with a depending shaft 153 carrying a roller 154 thereon, which roller is adapted to engage a gear 155 carried on a shaft 156. The shaft 156 extends laterally of the extension 147 30 and is supported by bearings 157. The shaft 156 carries a beveled gear 158 adapted to mesh with a beveled gear 159 carried on a traverse motion shaft 160. The beveled gear 159 is supported by a curved relatively small bracket 161 formed integral with the bracket 146. A feeder sleeve 162 is carried on the shaft 160 and is adapted to shift upwardly and downwardly as in the preferred form of the invention. Yarn receiving eyes 163 and 164 are carried at the upper and 40 lower ends, respectively, of said feeder sleeve. It will be understood that rotative motion from the spur gear 132 will be transmitted to the drive sleeve 128 through the gears 136, 135, the pinion 143, the gear 144, the gears 151 and 152, the 45 roller 154, the gear 155, shaft 156, beveled gears 158 and 159, to said shaft 160 for driving the shaft and effecting the shifting of the feeder sleeve. The yarn 116 will be trained about a roller 165 which is carried in the recess 120 and 50 will be led upwardly through a compressor 166 through the sleeve 138, over the roller 141, about the feed rollers 148 and 149, through the eyes 164 and 163 on the feeder sleeve 162, and thence to the stem 167 of a package or bobbin 168. The 55 package 168 is provided with a bottom portion 169 which is adapted to have its lower surface engaged with a friction disc 170 carried on a driving plate 171. The driving plate 171 is carried on the package mounting shaft 139 and is 60 adapted to be driven thereby through a pinion 172 which is fixed to the lower end portion of said package mounting shaft, and through gears 173 and 174, which are carried at the upper and lower sides of the lower portion 113 of the flyer 65 frame 110, and through the pinion 125 which is fixed to the drive shaft 122. Rotative motion of the package so that said package will be caused to 70 rotate independently of the flyer frame and traverse motion and will be caused to wind the yarn 116 about the package or bobbin, as in the preferred form of the invention. The gears 173 and 174 are keyed to a shaft 475, which shaft 475 is journaled in an integral sleeve 476. The pin- 75

ions 143 and 112 are separated by a bushing 112'. Generally speaking, the operation of the modification of the invention is similar to that of the preferred form, the main difference being that the feed rollers are adapted to rotate in the same direction, as will be seen by a study of Figure 9 of the drawings. Furthermore, in this form of the invention, provision has been made to eliminate stretching of the yarn while, at the same time, removing the possibility of permitting the yarn to become too loose.

It is believed that the operation of my invention may be readily understood.

Having thus described the invention, what I claim is:

1. In a twister, a flyer including a flyer frame, means for mounting the flyer frame including spaced arms, a former carried by said means between said arms and having a shaft, rollers carried by the former, means for permitting rotation of the former, said former shaft having a pinion, gears carried by one of said spaced arms, one of said gears meshing with said pinion, a gear carried by the flyer frame and meshing with the other of said gears, all of said gears being adapted to transmit rotative motion from the former to the flyer frame at a relatively reduced speed, and a package carried by the flyer frame, said former and flyer frame cooperating for twisting strands of yarn passing through the former and about said flyer frame to be wound upon said package.

2. In a twister, a flyer including a flyer frame, means for mounting the flyer frame, a former carried by said means, means for transmitting rotative movement to the former, gearing carried by said former, said former mounting means and said flyer frame for transmitting rotative movement at a reduced speed to said flyer frame from said former, said flyer frame having a trunnion and a package mounting shaft, a package carried by the flyer frame and mounted on said trunnion and said package mounting shaft, said package mounting shaft having a relatively large bracket secured thereto, feed rollers carried by the bracket, a traverse motion carried by the bracket, and means for driving the feed rollers, said traverse motion and the package, said former and flyer frame being adapted to cooperate to twist yarn passing therethrough and said yarn being adapted to be wound about said feed rollers, fed to the traverse motion and wound about the package at rotation of said package independently with respect to said flyer frame.

3. In a twister, a flyer having a frame, a package mounting shaft carried by the frame, a stationary shaft rotatably mounting the frame at its lower end, said stationary shaft having a pinion fixed thereto and said package mounting shaft having a pinion, gears carried by the frame and engageable with both of said pinions for limiting the stationary shaft and package mounting shaft against relative rotative movement as said frame is rotated, a relatively wide pinion carried by the package mounting shaft, gears carried by said stationary shaft and rotatable freely thereabout, gearing carried by the frame for communicating rotative movement from said gears on the stationary shaft to said relatively wide pinion, a worm engageable with one of the gears on said stationary shaft for communicating rotative movement through said gearing on the frame to said relatively wide pinion, a relatively large bracket carried by the package mounting shaft, feed rollers carried by the bracket, a package mounting disc carried by the package mount-

ing shaft and formed with an integral pinion, said package mounting disc being freely rotatable about said package mounting shaft, means carried by one of said feed rollers for communicating rotative movement from said relatively wide pinion to said package mounting disc, and a package carried by the package mounting shaft and being adapted to be rotated independently with respect to the frame for winding yarn twisted by said flyer frame and fed by said feed rollers onto said package.

4. In a twister, a frame, a package, a package mounting shaft carried by the frame for rotatably mounting the package therein, means carried below the frame for rotating the package, said package mounting shaft including a relatively large bracket, feed rollers carried by the bracket, a traverse motion carried by the bracket and including a shaft and a feeder sleeve, said shaft being adapted to be rotatably connected with the feed rollers for shifting the feeder sleeve and leading yarn twisted by and fed through the frame and feed rollers to the package whereby said yarn will be permitted to wind evenly on said package at rotation thereof, said first mentioned means being adapted for operating the feed rollers and shaft.

5. In a twister, a flyer having a frame provided with a spindle, a former having a shaft engageable with the spindle and being provided with a pulley, former rollers carried by the former, a yoke support having a pair of arms, one of said arms journaling said former shaft at its lower end, a gear carried by the spindle, a pinion carried by the former shaft, gearing carried by one of said arms for transmitting rotative movement at a reduced speed from said former shaft to said spindle whereby said flyer frame will be rotated, and means for rotatably mounting the lower end of said flyer frame.

6. In a twister, a flyer having a frame provided with top, side and bottom portions, said bottom portion having a relatively small bracket, means for rotatably mounting the frame at its upper end, means for imparting rotative movement to the frame, said top, side and bottom portions being hollow and certain of said portions being adapted to receive twisted threads therein, a compressor carried by the relatively small bracket, a package mounting shaft carried by the relatively small bracket and having a socket, a roller carried in a wall of the socket, a relatively large bracket carried by said package mounting shaft, feed rollers carried by the bracket, a traverse motion carried by the bracket, a package carried by the package mounting shaft, a stationary shaft rotatably mounting the lower end of said frame, and means carried by the stationary shaft, said frame, said package mounting shaft and said rollers for imparting rotative movement to said package independently of said frame, said compressor being adapted to receive therethrough twisted yarn by rotative movement of the frame and said yarn being fed over said roller in the wall of the socket about said feed rollers in criss-cross relation and thence to said traverse motion to be led therefrom and wound uniformly on the package as said package rotates.

7. In a device of the class described, a flyer including a frame having an inverted L-shaped bracket, a package mounting shaft carried on the bracket, means for rotatably mounting the frame at its lower end, said means having a pinion fixed thereon, gears carried by the frame, certain of said gears meshing with said pinion, a pinion

fixed to said package mounting shaft, certain other of said gears of the frame meshing with said last mentioned pinion, all of said gears co-operating to impart rotative movement from a point beneath the frame to said package mounting shaft, a bearing bracket formed integral with the frame and having a pinion, means engageable with the pinion for rotating the frame, a package mounting disc carried by the shaft, a package carried on said package mounting disc, said package mounting disc having a lateral bracket, feed rollers carried by the bracket, a traverse motion carried by the bracket and including a traverse motion shaft and a feeder sleeve, and means rotatably connecting one of said feed rollers with said traverse motion shaft, said frame being adapted to impart a double twist to threads passing thereon and said threads being adapted to pass about said feed rollers to said feeder sleeve and about the package as said frame and package are rotated with respect to each other.

8. In a twister, a flyer having a frame provided with a depending bearing bracket and an up-standing inverted L-shaped bracket, a drive shaft carried by the bearing bracket and having a pinion, a drive sleeve surrounding the drive shaft and being fixed to the bearing bracket, said bear-

ing bracket having a bight portion provided with a pinion, means engageable with the pinion for rotating the drive sleeve and the frame, a package mounting shaft carried by the inverted L-shaped bracket and having a socket, said package mounting shaft having a lateral bracket, feed rollers carried on the bracket, a package carried on the package mounting shaft, a pinion rotatable about said package mounting shaft, gearing for transmitting rotative movement from said drive sleeve through said pinion to said feed rollers and said package whereby said rollers and package will be rotated independently of said frame, a compressor carried by the inverted L-shaped bracket, a traverse motion carried by the lateral bracket and having a shaft and a feeder sleeve, and means rotatably connecting the traverse motion shaft with one of said feed rollers, said feeder sleeve being adapted to lead yarn carried on the frame and twisted thereby from said feed rollers to said package for uniform winding about said package as said package is rotated independently of the rotation of said frame, said uniform winding of yarn on the package permitting a high rate of speed of rotation of said frame about said package.

DANIEL W. MAXHAM.
